UNITED STATES PATENT OFFICE

93,010

DESIGN FOR A WEIGHING SCALE UNIT

Leroy N. Fredd, Pottstown, Pa., assignor to The Kron Co., Bridgeport, Conn., a corporation of Connecticut

Application August 19, 1933, Serial No. 49,059

Term of patent 14 years

To all whom it may concern:

Be it known that I, LEROY N. FREDD, a citizen of the United States, residing at Pottstown, in the county of Montgomery and State of Pennsylvania, have invented a new, original, and ornamental Design for a Weighing Scale Unit, of which the following is a specification, reference being had to the accompanying drawing, forming part thereof.

The figure is a perspective view of a weighing scale unit showing my new design.

I claim:

The ornamental design for a weighing scale unit, as shown.

LEROY N. FREDD. [L.S.]
